UNITED STATES PATENT OFFICE.

PETER BENJAMIN KAMEDISH, OF WINNIPEG, MANITOBA, CANADA.

SAFETY ATTACHMENT FOR LOCOMOTIVES.

Application filed October 20, 1923. Serial No. 669,820.

This invention relates to improvements in safety attachments for locomotives and has particular reference to a safety device for use in conjunction with a locomotive drifting attachment of the character set forth in my co-pending application, Number 521,418, filed on the 10th day of December, 1921.

The principal purpose of the present invention is to provide a device functional to prevent an idle locomotive, standing say at a round-house or on a side track with steam up and air on to start of itself in the event that the locomotive has a leaky throttle and some individual such as an engineer, hostler or machinist happens to cut off the air pressure.

A more general object is to provide, in combination with a steam valve normally held open against working steam pressure by a reacting air pressure, means for positively locking the valve open should the air pressure drop, said locking means being designed also to unlock the valve upon the air pressure subsequently building up.

Other objects and advantages of the invention as well as the characteristic features of the disclosed embodiment will be more readily understood from the following detailed description taken in connection with the accompanying drawings, in which,

Figure 1 is a side view of the front end of a locomotive equipped with my invention.

Figure 2 is an enlarged detailed vertical sectional view taken centrally through the safety attachment.

Figure 3 is a vertical sectional view taken along the line 3—3 of Figure 2 and,

Figure 4 is a vertical sectional view taken along the line 4—4 of Figure 2.

In the drawings like characters of reference indicate corresponding parts in the several figures.

The present safety device has been particularly designed for use in connection with the locomotive drifting attachment as fully described in my prior application herein referred to. In said drifting attachment it was possible for an idle locomotive standing, say, at a roundhouse or on a side track with the steam up and air on to start of itself provided such engine or locomotive had a leaky throttle and some individual such as an engineer, hostler or machinist cut off the air pressure.

The safety attachment, hereinafter described and forming the substance of this application is for the purpose of positively pre-

venting the engine or locomotive from starting under such a condition.

As the various parts of my drifting attachment are fully shown and described in my prior application I have not considered it necessary to herein enter into a detailed description or showing of the same, but will just refer to those parts with which my safety device is associated, and in this connection it is to be understood that such other parts are structurally the same and operate the same as disclosed in such prior application. I will also herein use the same reference numerals as used in such prior application to indicate those parts which are common to both applications.

The locomotive 1 presents the boiler shell 2, a smoke stack 3, a smoke box 4, a steam chest 5 containing the valve 6 and a dry steam pipe 7 having the upper end connected to the usual super-heater 8 and the forward end connected with the steam chest containing the engine valves.

A steam pipe 20* communicates through a suitable steam supply valve (not shown) with the dome of the boiler and connects forwardly with a T elbow 20² and the elbow is connected by means of a short pipe 20' with a steam controlling valve 20. The steam controlling valve is connected by a steam pipe 22 to the stand pipe 7, an intercepting valve 21 being introduced in the said pipe. In the pipe 22 I introduce a T elbow 22' which is connected by means of a steam pipe 23' to a double check valve 23. A steam pipe 23² connects the double check valve with the steam chest 5 and a steam pipe 23* connects the T elbow with the double check valve. A governing cylinder 24 is mounted adjacent the valve 20, the cylinder controlling the operation of the valve 20. An air cut off valve 26 is introduced in an air pipe 27 which communicates with an air controlling valve (not shown) and has the forward end thereof connected to an air cylinder 80. A return air pipe 28 leads from the cylinder 80 and connects with the air controlling valve. The valve 21 presents an interior vertically disposed dividing valve seat 73 which slidably receives the guides of the valve 75. The stem 78 of the valve is slidably mounted in the side of the valve casing and has the end projected therebeyond. The aforesaid cylinder 80 is axially aligned with said stem and between the cylinder and the casing of valve 21 I introduce my safety device which forms the

100
105
110

substance of the present invention and is for the purpose of positively locking valve 75 in opening position when the locomotive is standing idle under the conditions previously referred to.

The safety device is now described in detail. The valve stem 78 projects slidably through a suitable stuffing box 9 into a cylindrical casing 10, the casing 10 being attached 10 as by screw threading to the valve casing and being provided at the sides with similar inspection and escape openings 10'. The outer end of the casing 10 is closed by a screw plug 11, the inner end of which is provided 15 with a suitable stuffing box 12. The outer end of the plug is provided with an extending screw threaded nipple 13 to which the cylinder 80 is connected. A piston 14 is slidably mounted in the cylinder 80 and is provided 20 with a stem or push rod 15 which passes slidably through the plug 11 and the bushing 12 and enters the interior of the cylinder 10 and is adapted to engage with the adjacent end of the stem 78.

25 Here it will be observed that a clearance space is reserved between the bushings, that the stem 15 is axially aligned with the stem 78 and that the diameter of the stem 78 is considerably greater than the diameter of the 30 stem 15. Within this clearance space I locate a locking plunger 16 which has the lower end thereof slidably received within a boss 17 integrally cast with the cylinder 10. The lower end of the plunger terminates in a guide rod 35 16' which passes slidably through a screw plug 18' screw threaded into the lower end of a cylindrical shell 18 carried by the lower end of the boss 17. A lock nut 18" is placed on the plug 18' and a spring 19 surrounds 40 the rod and has one end bearing against the inner end of the plug 18' and the other end contacting with a washer 19' engaged with the shoulder of the plunger. The tension in the spring can be gauged by adjusting the 45 plug 18' and afterwards tightening up the lock nut, and the spring operates normally to hold the plunger in its uppermost position, that is with the lower side of the locking opening 16' of the plunger contacting 50 with the under side of the stem 15. The locking opening 16' passes transversely through the plunger and is circular and of slightly larger diameter than the projecting end of the stem 78.

55 By observing Figure 2 it will be seen that the stem 15 is within the opening 16' and contacting with the end of the stem 78 and is preventing the plunger 16 from rising further, and that the end of the stem 78 is engaging with the side of the plunger and in such position positively prevents the valve 75 from closing. It will also be observed 60 that should the plunger be forced down, the opening 16' will be brought into registration with the end of the stem 78 and accordingly

at this time should the pressure against the valve 75 be greater than the pressure in the cylinder 80 the valve will seat as the end of the stem 78 can then pass into the opening 16'. The upper end of the plunger is received within a sleeve like extension 29 of a piston 30, the piston operating within a cylinder 31 carried by the cylinder 10 and slidably receiving the sleeve 29. The cylinder 31 is screw threaded into the cylinder 10 and is 70 positively locked in position by a locking screw 32 and it is provided with a removable head or cap 33. This arrangement allows the plunger to be readily removed and the valve dismounted from the plunger. An air pipe 34 leads from the upper end of the cylinder to a source of air supply and in reality would be actually connected to the main air reservoir (not shown) of the locomotive.

With my drifting attachment including 85 the safety device of the present invention installed on a locomotive it is impossible for such locomotive, when standing idle with steam up and air in the pipes 34 and 27 to start, by reason of a leaky throttle, in the 90 event that someone should release the air pressure in the pipes 34 and 27. Under such a condition the plunger acting under the influence of the spring will lock the stem 78 and consequently the valve 75 open. In this connection I might explain that the steam leaking past the throttle passes upwardly through the pipe 22 to the valve 75 and if the 95 said valve be locked positively open as above explained and under the conditions outlined 100 such leaking steam cannot build up in the stand pipe 7 as it is free to escape through the pipe 23', valve 23 and pipe 23", to the exhaust passages of the engine.

Under the working conditions of the engine 105 there is air under pressure direct from the reservoir in the cylinder 31 and air pressure in the cylinder 80 controlled by the cut off valve 26 and the pressure of the air in the cylinder 31 holds the plunger down against 110 the pressure of the spring and with the opening 16' thereof directly opposing the end of the stem 78 with the result that the valve 75 can close at any time the air pressure in the cylinder 80 is cut off. Accordingly the 115 valve 75 is free to function in the same manner as described in my prior application, opening and closing under the varying pressure conditions of the steam in the pipe 22, and the air in the cylinder 80.

120 The safety attachment, however, will act to lock the valve 75 positively open under the conditions hereinbefore mentioned for the reason that should an engineer, hostler, mechanic or other person cut off the air such 125 would reduce the air pressure in the cylinder 31 to atmosphere and would accordingly permit the plunger to move up quickly under the action of the spring and lock the valve stem 78 in the manner shown in the 130

drawings which is the open position of the valve 75. The said valve being locked open steam cannot build up in the stand pipe 7 with the result that the engine will remain standing still. The instant, however, that air pressure is available at the cylinder 31 the safety device is thrown out of commission as the plunger is dropped to permit the valve stem to pass into the opening 16' with the result that the said valve is then free to function entirely independent of the locking device.

What I claim as my invention is:

1. The combination with a steam controlling valve, the said valve being provided with an extending stem and a pressure operated piston having an extending stem engaging with the former stem and maintaining the valve open, of a spring pressed locking plunger to travel across the path of the valve stem and a pressure operated piston associated with the plunger and holding the plunger clear of the valve stem during the period that there is pressure against both pistons and freeing the plunger to travel across the path of the valve stem under the pressure of the spring and lock the same against movement upon a reduction of the pressure occurring simultaneously in the cylinders.

2. The combination with a valve casing and a steam controlling valve mounted within the casing and provided with an extending stem, of a compressed air receiving cylinder adjoining the casing, a piston mounted within the air cylinder and provided with an extending stem axially aligned with the valve stem to contact with the valve stem and hold the valve open under pressure of air within the cylinder, a spring pressed locking

plunger, a piston associated with the plunger, a cylinder slidably receiving the piston and connected with a source of compressed air supply, the pressure of the air inside the latter cylinder maintaining the plunger free of the valve stem and said plunger upon the reduction of the air pressure in the cylinder travelling across the path of the valve stem and locking the same against movement with the valve open.

3. The combination with a valve casing and a steam controlling valve within the casing, said valve being supplied with an extending stem, of an air cylinder in communication with a source of compressed air supply, a piston within the cylinder and provided with an extending stem of less diameter than the valve stem and engageable therewith to hold the valve open under the pressure of the air within the cylinder, a locking plunger located at the end of the valve stem and provided with an opening receiving the piston stem, said opening being large enough to permit of the passage of the valve stem, a piston associated with one end of the plunger, a cylinder receiving the piston and in communication with a source of compressed air supply, said piston under the pressure of the air within said latter cylinder holding the plunger with the opening therein axially aligned with the valve stem and a spring associated with the plunger for shifting the same into the path of the valve stem to hold the valve open, said spring operating upon the pressure of the air in the cylinders being simultaneously reduced.

Signed at Winnipeg, this 25th day of September 1923.

PETER BENJAMIN KAMEDISH.
